UNITED STATES PATENT OFFICE.

ROBERT E. VANDERGRIFF, OF FELLOWS, CALIFORNIA.

DRILL.

1,090,952.

Specification of Letters Patent. Patented Mar. 24, 1914.

Application filed September 13, 1913. Serial No. 789,681.

To all whom it may concern:

Be it known that I, ROBERT E. VANDERGRIFF, a citizen of the United States, residing at Fellows, in the county of Kern and State 5 of California, have invented certain new and useful Improvements in Drills, of which the following is a specification, reference being had to the accompanying drawings,

This invention relates to certain improvements in drills and has relation more particularly to a device of this general character especially designed and adapted for use in working stone and the object of the invention is to provide a drill of this general 15 character wherein the cutting portions are comprised of a plurality of disks designed to rotate and including means of a novel and improved character whereby the disks are permitted to rotate with a minimum of friction 20 and wherein the mountings of the disks are effectually guarded against interference from foreign substances such as dirt or the like.

The invention consists in the details of 25 construction and in the combination and arrangement of the several parts whereby certain important advantages are attained and the device is rendered simpler, less expensive and otherwise more convenient and advantageous for use, all as will be hereinafter 30 more fully set forth.

The novel features of the invention will be carefully defined in the appended claims.

In order that my invention may be the 35 better understood, I will now proceed to describe the same with reference to the accompanying drawings, wherein—

Figure 1 is an enlarged sectional view taken through coacting rotary disks or bits 40 constructed in accordance with my invention; Fig. 2 is a view in rear elevation, on a smaller scale, of one of the rotary disks or bits, as herein disclosed; Fig. 3 is a view in front elevation of a disk or bit, as herein 45 disclosed, in applied position, the projecting portion of the supporting leg with which such disk coacts being omitted; Fig. 4 is a view in elevation on a smaller scale of a drill head with bits or disks constructed in accordance with my invention applied thereto; and Fig. 5 is a sectional view on a reduced scale taken transversely through one of the disks or bits.

As disclosed in the accompanying draw-

ings, 1 denotes the drill head provided at one 55 end with a screw-threaded stem 2 adapted to be engaged with a drill rod or tube or to any other means whereby the head may be rotated. The opposite end of the head is provided with the spaced legs 3—3 so twisted 60 as to occupy parallel planes extending diagonally relatively to the faces of the head 1.

In close proximity to the free ends of each of the legs and adjacent the inner face thereof is secured the cutting disks or bits 4 concavo-convexed in form and being provided with a central hub 5 whereby such disk may be rotatably mounted on the bearing pin 7. Each of the bearing pins 7 extends entirely 70 through the coacting leg 3, and as herein shown is secured thereto through the medium of a reduced threaded portion 8 adapted for engagement with the threaded opening 9 suitably produced in the leg. The 75 inward movement of the pin 7 relatively to the leg is limited by the annular shoulder 10 abutting with the inner face of the adjacent portion of the leg 3.

The pin 7 has its innermost end provided 80 with a head 11 adapted to limit any endwise movement of the disk 4 relatively to the pin, such head 11 serving to snugly hold the disk 4 in close proximity to the adjacent face of the coacting leg 3. In order that the disk 85 4 may rotate about the pin 7 with a minimum of friction, I produce in the hub 5 an annular seat 14 adapted to accommodate roller bearings 15 such roller bearings being maintained against displacement by the head 90 11, as is believed to be clearly obvious from the drawings, and such rollers 15 are adapted to contact with the adjacent surface of the pin 7 and serve as an anti-friction means, as is believed to be clearly apparent. 95

The outer portion of the hub 5 is extended, as at 16, and has its periphery screw-threaded in order to be detachably engaged by the inclosing cap 17 disposed about the head 11 but rotatable with the disk 4, such cap 17 100 serving as a convenient and effective means for precluding the entrance of any foreign substances, such as dirt or the like within the hub 5 of the disk, as would otherwise tend to interfere with the rotation thereof. I 105 also find it of advantage to preclude the entrance of any foreign substances within the hub 5 from the inner end through the pro-

vision of the annular flange 18 formed on the inner face of the leg 3 in which the pin 7 is snugly seated while the inner end portion of the hub 5 is provided with the annular recess 19 adjacent its bore and adapted to snugly accommodate such flange 18. The annular recess 19 is of a depth greater than the height or thickness of the annular flange 18 in order that there may be interposed between the outer face of the flange 18 and the base of the recess 19 the gasket 20 which may be produced of any ordinary or preferred material.

Although forming no part of the present invention, it will be well to state that longitudinally of the head 1 are afforded the water-passages 21—21, as is customary in drills of this general character.

From the foregoing description, it is thought to be obvious that a drill constructed in accordance with my invention is of a simple and comparatively inexpensive nature and is particularly well adapted for use by reason of the particular mountings for the rotary disks or bits whereby the same are permitted to operate with a minimum of friction and are effectually protected against any foreign substances as would interfere therewith and it will also be obvious from the foregoing description that my invention is capable of some change and modification without material departure from the principles and scope thereof and for this reason I do not wish to be understood as limiting myself to the precise arrangement and forma-

tion of the several parts, herein shown, in carrying out my invention in practice.

I claim:

1. A drill including a head having spaced legs, a pin detachably secured to each of the legs, a disk rotatably supported on the pin, such disk having a projected hub portion, and a closure detachably engaging the projected hub portion and inclosing the pin.

2. A drill including a head having spaced legs, a pin inwardly projected from each of the legs and terminating in a head, a disk rotatably mounted on the pin, the hub portion of such disk having a plurality of recesses provided in the face of the hub portion adjacent the pin, and rollers seated within one of the recesses and adapted to contact with the pin.

3. A device of the character described including a leg, a pin projecting from such leg, an annular flange on the leg surrounding the pin and adapted to contact therewith, a disk mounted on the pin and having an annular recess in its hub portion adapted to accommodate the flange of the leg, and a gasket surrounding such pin and interposed between the flange of the leg and the base of the recess of the disk.

In testimony whereof I hereunto affix my signature in the presence of two witnesses. 65

ROBERT E. VANDERGRIFF.
